No. 841,452.

R. RUTHERFORD. PATENTED JAN. 15, 1907.
BOAT PROPELLING MECHANISM.
APPLICATION FILED JAN. 16, 1906.

Fig. 1.

UNITED STATES PATENT OFFICE.

ROBERT RUTHERFORD, OF MONTAVILLE, OREGON.

BOAT-PROPELLING MECHANISM.

No. 841,452.

Specification of Letters Patent.

Patented Jan. 15, 1907.

Application filed January 16, 1906. Serial No. 296,278.

To all whom it may concern:

Be it known that I, ROBERT RUTHERFORD, a citizen of the United States, and a resident of Montaville, in the county of Multnomah and State of Oregon, have invented a new and Improved Boat-Propelling Mechanism, of which the following is a full, clear, and exact description.

The invention relates to a peculiar device for manually propelling boats and smaller marine vessels by means of a screw-propeller.

In carrying out my invention I mount the propeller on the shaft as usual, and I connect the same with a double crank-shaft within the boat. In this crank-shaft is fastened a fly wheel or wheels, and above the same is erected a scaffold on which is arranged a walking-beam. The walking-beam has a peculiar handle, by means of which it may be rocked by an operator seated, preferably, on the stern-sheets of the boat, and said walking-beam has peculiarly-arranged connecting-rods joining its ends with the crank-shaft. The walking-beam extends fore and aft to facilitate its manual operation, and the connecting-rods are allowed a lateral swinging movement on the walking-beam to accommodate the throw of the cranks and are further allowed a fore-and-aft swinging movement to accommodate the throw or arc through which the ends of the walking-beam move.

Reference is to be had to the accompanying drawings, which illustrate as an example the preferred embodiment of my invention.

In the drawings, Figure 1 is a longitudinal section of a boat equipped with my invention. Fig. 2 is an enlarged side elevation of the motor. Fig. 3 is a front view of the same, and Fig. 4 is a detail section showing the joint between the walking-beam and the connecting-rod.

As shown in Fig. 1, the propeller 10 is mounted aft of the stern-post of the boat on its shaft 11 in the usual manner. Said shaft is coupled to a crank-shaft 12, (best shown in Fig. 2,) which is mounted in bearings 14, carried in a suitable bed 15. Erected on said bed is a scaffold or frame 16, having a journal 17 therein which carries the walking-beam 19. Said walking-beam is arranged within the scaffold and extends fore and aft of the boat. Secured to the walking-beam, preferably at the middle thereof, is a tubular arm 20, in which a pin 21 is adjustably held by means of a set-screw or other device 22. Said pin 21 carries at its upper end a trans-

verse handle 23, and through this handle and its connections 21 and 22 the walking-beam may be rocked upon the horizontal axis of the journal 17.

The ends of the walking-beam are formed with sockets 24 therein, (best shown in Fig. 4,) and in said sockets are arranged the spherical upper ends 25 of the connecting-rods. Said spherical ends 25 are held in the sockets 24 and are allowed a universal movement therein through a limited arc by means of pins 27^a, which pass through the walls of the socket members. The connecting-rods are composed of upper members 26, which telescope into tubular sections 27.

28 indicates set-screws for holding the parts 27 and 26 in the desired adjustment. The sections 27 have joints 29 connecting them with the lower sections 30 of the connecting-rods. The ball-and-socket connections 24 and 25 permit the connecting-rods to swing thwartships to allow for the movement of the crank 12, while the joints 29 permit the upper parts 26 and 27 of the connecting-rods to swing fore and aft to accommodate the arcs in which the ends of the walking-beam move.

It will thus be seen that an operator seated on the stern-sheets of the boat or, if desired, two operators, one seated on the stern-sheets and one on the after-thwart, may, through the means of the handle 23 and its connections, rock the walking-beam 19, imparting a rotary movement to the crank-shaft 12 and to the propeller-shaft 11, which is coupled thereto. In this manner the propeller may be rapidly driven and the boat propelled.

Having thus described the preferred form of my invention, what I claim as new, and desire to secure by Letters Patent, is—

1. In a boat-propelling mechanism, the combination of a crank-shaft, a member extending longitudinally of the crank-shaft and rocking around an axis transverse thereto, and means connecting the ends of said member with the crank, said means having a vibratory movement on said member to accommodate the throw of the crank, and also having a vibratory movement longitudinal of the shaft to accommodate the arc in which the said member swings.

2. In a boat-propelling mechanism, the combination of a crank-shaft, a member arranged to swing around an axis transverse to the crank, a connecting-rod joined to the crank-shaft and having a ball-and-socket con-

nection with said member, the connecting-rod also having a joint therein permitting a part of the rod to move in a plane extending longitudinally of the crank-shaft.

5 3. In a boat-propelling mechanism, the combination of a double crank-shaft, a walking-beam extending longitudinally of the crank-shaft, a handle secured to the walking-beam, and connecting-rods joining the ends 10 of said beam respectively with the cranks of the shaft.

4. In a boat-propelling mechanism, the combination of a double crank-shaft, a walking-beam extending longitudinally of the crank-shaft and rocking around an axis transverse thereto, and connecting-rods joining the ends of the walking-beam respectively 15 with the cranks, said connecting-rods having vibratory movement on the walking-beam to accommodate the throw of the cranks, and the portions of the rods in connection with the walking-beam having movement longitudinally of the crank-shaft to accommodate 20 the swing of the ends thereof.

25 5. In a boat-propelling mechanism, the combination of a double crank-shaft, a walking-beam arranged to rock around an axis

transverse thereto, said walking-beam having socket members at its ends, and connecting-rods having spherical ends working in the 30 socket members, the connecting-rods being joined respectively to the cranks and having joints therein permitting the parts of the rods in connection with the walking-beam to move longitudinally of the shaft to accommodate 35 the movement of the walking-beam.

6. In a boat-propelling mechanism, the combination of a double crank-shaft, a scaffold rising therefrom, a walking-beam extending longitudinally of the crank-shaft and 40 mounted on the scaffold, connecting-rods joining the ends of the walking-beam to the crank-shaft, a tubular arm projecting from the walking-beam, and a handle member having a part adjustably fitted in the said tubular arm.

In testimony whereof I have signed my name to this specification in the presence of two subscribing witnesses.

ROBERT RUTHERFORD.
